UNITED STATES PATENT OFFICE.

FRANK H. CHASE, OF CHICAGO, ILLINOIS.

REFRIGERATOR.

1,056,885.

Specification of Letters Patent. Patented Mar. 25, 1913.

Application filed June 15, 1912. Serial No. 703,820.

To all whom it may concern:

Be it known that I, FRANK H. CHASE, a citizen of the United States, residing at Chicago, in the county of Cook and State of Illinois, have invented certain new and useful Improvements in Refrigerators, as set forth in the following specification.

My invention relates in general to refrigerators, and particularly to refrigerators of the type which is adapted to be positioned beneath the surface of the ground, depending upon the temperature of the earth for its cooling properties.

One of the principal objects of the invention is to provide a refrigerator which may be quickly and easily positioned within and removed from the earth, and which shall be particularly adapted to the use of campers and others who wish a cooling apparatus which may be moved from place to place and readily positioned for use.

A further object of the invention is to provide a refrigerator of the character described which will be perfectly ventilated at all times, and so constructed that the air within the provision chamber will be changed every time articles are put in or removed therefrom.

Another aim of my invention is to provide a refrigerator of the type described which will be cheap to manufacture, simple of construction, and which will occupy a minimum space when not in use.

Further aims and advantages of the invention will be apparent as it is better understood from the following description which, taken in connection with the accompanying drawings, discloses one preferred embodiment thereof.

On the drawings:—Figure 1 is a vertical sectional view of a refrigerator made in pursuance of my invention in operative position in the ground; Fig. 2 is an enlarged horizontal sectional view on the line 2—2 of Fig. 1; Fig. 3 is also an enlarged horizontal sectional view which is taken on the line 3—3 of Fig. 1, and Fig. 4 is a fragmentary vertical sectional view showing the means connecting the receptacle-receiving angle-irons to the side members of the frame.

On the drawings, an outer casing or member 10 is formed of a plurality of cylindrical sections 11 which are joined together by the interlocking ribs 12 constructed to provide a comparatively smooth surface within the member. The member 10 is provided at

its bottom with a closure 13, and at a substantial distance beneath its top with the pipe-receiving sockets 14 communicating with the interior of the member. In these sockets are fastened in suitable manner the outwardly extending pipes 15 provided at their ends with the elbows 16, into which are secured the upwardly extending pipes 17. The pipes 17 are of sufficient length to extend above the top of the member 10 so that when the refrigerator is in use their ends will be disposed a substantial distance above the surface of the ground. Each is provided at its upper extremity with a T 18, through which atmospheric air is admitted to the interior of the member by means of pipes 19, elbows 20 and pipes 19' secured in the elbows. The pipes 19' are preferably disposed downwardly from the elbows 20 to prevent rain-water from entering and lodging in the chamber 10. The T's 18 are connected by the U-shaped pipe or solid rod 21, which extends above the member a distance somewhat greater than the length of the member. A second hollow member 22 closed at its bottom 23 and of substantially less dimensions than those of the member 10 is provided at its top with a downwardly inclined and outwardly disposed flange 24 extending about its upper peripheral edge. This flange is of sufficient width to permit it to extend over the top of the member 10, supporting the member 22 in proper position and sealing the space formed between the two members.

A cover 25 is provided for the member 22 and is preferably made in the form of a sheet-metal box formed to fit closely within the member 22 and filled with asbestos or other suitable non-heat-conducting material 26, the sheet 27 forming the top of the said cover extending beyond the sides of the cover to form an outwardly extending annular flange 28, the outer edge 29 of which is bent downwardly and adapted to rest upon the flange 24 of the member 22, forming an air chamber between the flanges 28 and 24. To more perfectly seal this air space, and to effect a more perfect closure for the member 22, I provide suitable packing 31 upon the top of the flange 24 against which the downwardly turned edge 29 of the flange 28 rests. Through the center of the cover in a suitable aperture is rigidly fastened a pipe 32 closed at its ends and provided with apertures 33 and 34, the aper-

tures 34 being disposed above the cover and the apertures 33 below. Adjacent the bottom of the member 22 are provided a plurality of apertures 35, establishing communication between the chamber within the member 22 and the space between the walls of the members. Thus it is apparent that the interior of the chamber is in communication with the outer air through three paths, two leading from the pipes 19' through the pipes 19, 17 and 15, down between the walls of the two members 10 and 22, and into the bottom of the member 22 via the apertures 35, and one leading out of the top of the member via the pipe 32 through apertures 33 and 34.

To prevent insects, dirt, etc., from entering the member 22, I cover the ends of the pipe 19' and the apertures 33, 34 and 35 with gauze, wire or other suitable material 40 adapted to permit the free entrance of air, but to restrain the admission of objectionable insects or dirt.

Within the member 22 is suspended a frame 36 adapted to receive a plurality of receptacles 37 containing the articles to be kept cool. This frame consists of a stiff strap 38 bent in U-shape form to which circular supports 39 are fastened at intervals by means of rivets, bolts or other suitable fasteners 41. The receptacles 37 are preferably circular in form, and of a diameter adapting them to fit easily within the vertical walls 42 of the supports 39, to rest upon and be supported by the horizontal flanges 43 of these supports. The bottoms of all but the lowermost of these receptacles are perforated to permit the free passage of air around the articles carried thereby, and are shown in the present embodiment as having their bottoms formed of heavy wire gauze 44. The lowermost receptacle preferably has a solid imperforate bottom which acts, when the frame is lifted or lowered, much as the piston of an air pump, forcing the air within the member 22 out at the top when the frame ascends and out through the apertures 35, up between the walls of the members 10 and 22 and eventually out through the pipes 19' when the frame is lowered. Thus each time the frame is lifted out of the refrigerator practically a complete change of air in the inner chamber is effected.

The frame 36 is suspended from the cover 25 by means of the links 45 and 46, the latter link extending through and being fastened within the pipe 32. A pair of pulleys 47 and a rope 48 connect the upper end of the link 46 with a clevis 49 carried by the U-shaped pipe 21 at its top, and provide means for raising the cover and the frame with its receptacles.

At the bottom of the pipe 32 and immediately below the aperture 33 is secured a

cup 52 encircling the pipe, and above the cover a similar cup 53 is fastened. These cups are adapted to contain water or, if desired, poison, and are provided to prevent emmets and other small creeping insects from entering the member 22 by working through the gauze or wire 40. Upon the upper end of the pipe 32 is provided a shield 51 to prevent rain from beating in through the aperture 34 and wetting the contents of the refrigerator or flooding the upper cup.

It will here be noted that the present refrigerator includes a casing having inner and outer spaced walls 22 and 10, defining an annular air space which is in communication with the atmosphere through the pipes 15 and 17 and the elbow 20, and with the interior of the casing through the opening 35 in the lower part of the inner wall 22. Moreover the interior of the casing is in direct communication with the atmosphere through the pipe 32 which extends through the cover. The receptacle for containing the food has a slidible fit within the casing and constitutes a plunger to expel air from and draw air into the refrigerator through the two communications with the atmosphere.

When it is desired to position a refrigerator made in pursuance of my invention in the ground it is only necessary that a hole of suitable diameter be bored by an earth-auger or otherwise formed, sufficient earth being removed on opposite sides of the hole to receive the pipes 15 and 17, and the member 10 inserted therein. Into the member 10 may then be lowered the member 22, and the pulleys, cover and frame-work put in place. The whole refrigerator may be easily lifted out of the ground and moved to another locality by uncovering the pipes 15, if earth has been positioned thereabove. It is apparent that the U-shaped pipe 21 may be moved around the pipes 15 as a center until the top of the pipe is disposed behind the bottom of the member 10, thereby reducing the compass of the refrigerator materially when it is desired to store the refrigerator or to load it on a wagon on moving to another locality.

It will be manifest that numerous changes may be made in the form, construction and arrangement of the parts without departing from the spirit or scope of my invention or sacrificing any of its advantages, the form hereinbefore disclosed being merely one preferred embodiment thereof.

I claim:—

1. A refrigerator including a casing having inner and outer spaced walls defining an annular air space which is in communication with the interior of the casing, a frame rising from the casing and including a tubular part communicating between the atmosphere and the annular air space, said air

space also being in communication with the interior of the casing, a receptacle having a working fit in the casing and constituting a plunger to expel air from and draw air into the casing, and hoisting means suspended from the frame and connected with the receptacle.

2. In a refrigerator, the combination of a casing adapted to be positioned in the ground, a hollow member of diameter less than that of the casing adapted to be positioned within the said casing and provided with an aperture at its bottom, means for admitting air beneath the surface of the ground into the space between the casing and member, a cover sealing the top of the said member, and a pipe disposed through the said cover and provided with apertures both above and beneath the said cover, whereby air is admitted to the casing beneath the ground, permitted to pass through the apertures at the bottom of the member and out through the pipe positioned through the cover.

25 3. In a refrigerator, the combination of a casing adapted to be positioned in the ground, a hollow member of diameter less

than that of the casing adapted to be positioned within the said casing and provided with gauze-covered apertures at its bottom, 30 means for admitting air between the casing and member, a cover sealing the top of the said member, and a pipe disposed through the said cover and provided with gauze-covered apertures both above and beneath 35 the said cover, whereby air is admitted to the casing beneath the ground, permitted to pass through the gauze-covered apertures at the bottom of the member and out through the pipe positioned through the cover. 40

4. In a refrigerator, the combination of a hollow member adapted to be positioned beneath the surface of the ground, a cover for the said member, a pipe closed at both ends and provided with an aperture adjacent each end disposed through the said cover, and a cup disposed beneath an aperture and adapted to contain a liquid to prevent insects from entering the said member. 45
